RELEASABLE MARINE ANCHOR
William M. Sarns, Rte. 2, Morley, Mich.
Filed Mar. 1, 1961, Ser. No. 92,604
3 Claims. (Cl. 114—208)

This invention relates to the construction of anchors intended primarily for the use with small boats. The so-called "patent" anchor—a name commonly given to the general type of anchor having flukes which are rotatable within a limited sector with respect to the shank of the anchor—has come into very wide acceptance as a result of the tremendous holding power of this design for a given weight. The limited rotatability of the flukes with respect to the shank causes the anchor to dig in, regardless of the movement across the bottom.

A problem has arisen, however, which is actually the result of the extremely efficient action of the anchor. Once the anchor becomes deeply embedded, it is quite a project to withdraw it when the anchor is raised. Normal procedure in this regard is to haul in the anchor line with the boat in the position directly above the anchor. If normal lifting forces do not succeed in withdrawing it, the anchor line may be cleated on the boat, and the boat moved in a direction opposite from which the anchor was originally engaged. If the boat has been held during fairly heavy weather, even this procedure is sometimes inadequate. The problem is particularly aggravated in situations involving adverse bottom conditions such as rocks, tree stumps, sunken logs, etc. The limited sector of rotation of the flukes with respect to the shank creates a hook-shaped relationship in side elevation which almost prevents removal. Many are the anchors that have been left in place after several attempts to remove it, with the cost of the anchor line being added to that of the anchor itself as an investment lost beyond recovery.

Applicant has found that it is entirely practical to incorporate in the usual articulating anchor an arrangement for establishing the sector of free movement with respect to the shank through a torque-limiting device rather than a positive stop. The particular torque is established according to the needs of the boat and the bottom characteristics, and the net result is that a securely-embedded anchor can be released very easily. A heavy vertical pull on the anchor will create a torque on the shank in excess of the established limit, and will then permit the flukes to move to a feathered position trailing behind the shank. This will permit very easy withdrawal, regardless of the conditions of the retention of the anchor. If this direct-lift procedure proves to be inadequate, the cleating of the anchor line and the maneuvering of the boat under power or oars will almost invariably succeed in swinging the anchor to the feathering position and pulling it free.

The several features of the invention will be analyzed in further detail through a discussion of the particular embodiments illustrated in the accompanying drawing. In the drawing:

FIGURE 1 presents a perspective view of an articulating anchor embodying this invention.

FIGURE 2 presents a plan view, partially in section, showing the normal holding position of the anchor.

FIGURE 3 is a view in side elevation of the unit in the position shown in FIGURE 2, FIGURES 2 and 3 being in projection.

FIGURE 4 is a plan view, partially in section, showing the anchor in a position outside the normal sector of rotation of the flukes, corresponding to the movement toward the feathered position.

FIGURE 5 is a side elevation of the unit in the position shown in FIGURE 4, FIGURES 4 and 5 being in projection.

2

FIGURE 6 is a section on an enlarged scale on the plane VI—VI of FIGURE 3.

FIGURE 7 is a view on the plane VII—VII of FIGURE 5.

5 FIGURE 8 is a view on the plane VIII—VIII of FIGURE 5.

Referring to the drawing, the illustrated articulating anchor includes a shank 10 having a central hub 11 carrying the pin 12 on which the flukes 13 and 14 are rotatably mounted. Referring particularly to FIGURE 7, the flukes are provided with a lateral extension along the pin 12 as shown at 15 and 16, these extensions being received within the hub 11.

The flukes are preferably axially slidable along the pin 12, and are urged together through the action of the spring 17. The nut 18 and the head 19 of the pin 12 retain the flukes in engagement with the pin, with the spring establishing a tendency to drive both flukes toward the hub 11. This action tends to maintain the engagement of the V-shaped surfaces 20 and 21 on the extensions 15 and 16 of the flukes, respectively, which causes the flukes to maintain a position in the same plane. The spring action has the additional function of bringing the abutments 22 and 23 into engagement with the opposite abutment 24 on the shank to establish the normal free sector of rotation of the fluke 13 with respect to the shank. Similarly, the abutments 25 and 26 are engaged by the shank abutment 27 to establish the normal free articulation of the fluke 14. It is preferable that the plates 28 and 29 be cast integrally with the flukes 13 and 14, respectively, and the abutments 22, 23, 25, and 26 may be integrally cast or provided as added components.

The engagement of the fluke and shank abutments will establish a releasable limit for determining the normal sector of articulation of the flukes with respect to the shank, but this releasable limit is determined by the force provided by the spring 17. If a torque delivered to the anchor as a result of a severe pull on the anchor line exceeds the limit established by the abutments and the spring, the result will be a compression of the spring 17 to a degree which will permit fluke abutments to move over and around the shank abutments. The anchor will then move at least partially to a feathering position in which the flukes trail from the pin in a direction opposite from the line of tension established by the shank 10. The formation of the ends 20 and 21 on the fluke extensions within the hub 11 is such as to create a cam action tending to separate the flukes against the action of the spring 17 to facilitate the movement of the fluke abutments around the shank abutments, particularly when only one fluke becomes engaged with some form of bottom irregularity. In any event, the formation of these will establish a tendency to operate as a key to maintain the relative angular position of the flukes about the pin, and will provide a restorative action tending to re-align the flukes after they have been displaced.

The particular embodiments of the present invention which have been illustrated and discussed herein are for illustrative purposes only and are not to be considered as 60 a limitation upon the scope of the appended claims. In these claims, it is my intent to claim the entire invention disclosed herein, except as I am limited by the prior art.

I claim:

1. An anchor comprising: a shank having a hub with a central bore; a pin traversing said bore; fluke means rotatably and slideably mounted on said pin on opposite sides of said shank, said fluke means having axially interengageable key means to maintain the relative angular position thereof about said pin; interengageable abutment means on said shank and fluke means, respectively, to define opposite extremes of normal freedom of angular movement between said shank and fluke means, said

abutment means having configuration tending on engagement to induce axial separation between said shank and fluke means; and biasing means including a coiled compression spring surrounding said pin urging said shank and fluke means axially together.

2. An anchor comprising: a shank having a hub with a central bore; a pin traversing said bore; fluke means rotatably and slideably mounted on said pin on opposite sides of said shank; interengageable abutment means on said shank and fluke means, respectively, to define opposite extremes of normal freedom of angular movement between said shank and fluke means, said abutment means having configuration tending on engagement to induce axial separation between said shank and fluke means; and biasing means including a coiled compression spring surrounding said pin urging said shank and fluke means axially together.

3. An anchor comprising: a shank; a pin traversing said shank; fluke means rotatably and slideably mounted on said pin; interengageable abutment means on said shank and fluke means, respectively, to define opposite extremes of normal freedom of angular movement between said shank and fluke means, said abutment means having configuration tending on engagement to induce axial separation between said shank and fluke means; and biasing means urging said shank and fluke means axially together.
